Primary Examiner — Cynthia M. Chin

CLAIM

The ornamental design for a toy motorcycle, as shown and described.

DESCRIPTION

FIG. 1 is a front, right and top perspective view of a toy motorcycle showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the toy motorcycle that form no part of the claimed design.
